CARL BURHENNE.

Irving R. McElroy
ATTORNEY

UNITED STATES PATENT OFFICE.

CARL BURHENNE, OF RICHMOND HILL, NEW YORK.

WINDOW STOP.

Application filed February 18, 1928. Serial No. 255,359.

This invention relates to window stops and in particular to one of an adjustable nature.

A particular object of my invention is to provide a window stop which may be adjusted to permit the window to be opened fully or may be moved to a position to limit the opening movement of either the upper or lower sash.

A still further object of my invention is to provide an adjustable window stop which may be attached to the upper sash and which has a portion thereof arranged to overlie the lower sash when the same is released, there being provided in connection therewith a movable catch member which is arranged to retain the movable portion of the stop out of way of the lower sash when it is desired to fully open either the lower or upper sash.

A still further object of the invention is to provide a simplified construction in adjustable window stops which will prevent an intruder from operating the same from outside the window with a stick in order to open the window to gain admission to the room.

In devices of this nature, the construction has permitted an intruder to operate the same with a stick so that they will automatically remain closed when once closed and consequently permit the sashes to be moved relatively to each other so that admission can be gained through the window. In my invention, I have provided a pivotal catch member and two operations are necessary in closing the stop so that unlimited movement of the sashes relatively to each other can be accomplished.

To enable others skilled in the art to fully comprehend the underlying features of my invention that they may embody the same in the various modifications in structure and relation contemplated, a drawing depicting a preferred form has been annexed as a part of this disclosure and in such drawings, similar reference characters denote corresponding parts throughout all the views, of which,

Figure 1 is a view in perspective showing the arrangement of my improved window stop used in connection with an upper sash, the movable part of the stop being arranged to overlie the lower sash to limit the relative movement of both sashes, and

Figure 2 is a top plan view of the window stop showing how the same is arranged in connection with the upper sash and when closed, is compact enough to permit the lower sash to be passed thereover, thus allowing

free relative movement of the upper and lower sashes.

Referring to the drawings in detail, 5 indicates a base plate provided at one edge with 60 the ears 7, the same being formed in spaced relation and being arranged to receive the hinge pin 8 which also passes through the ears 9 formed on one edge of a locking wing member 10. The wing member or latching 65 plate 10 is arranged for pivotal movement relatively to the plate 5 and being normally positioned at right angles thereto through the medium of the coil spring 11 whose end 12 passes under a suitable punched out section 70 of material 13 in the latching plate 10, while the opposite end of the spring 14 passes through a similar punched out portion 15 in the base plate 5. The base plate is secured to the upper sash 17 through the medium of the 75 screw 16 and is firmly held in position on the upper sash at a distance above the upper end of the lower sash to prevent intrusion of an individual beneath the lower sash when the same has been raised against the lower in- 80 turned edge 18 of the latching plate 10. This inturned edge 18 provides a bearing foot against which the lower sash strikes and is limited in its upward movement.

The temper of the spring 11 which is positioned about the hinge pin 8 intermediate the ears 7 formed on the base plate 5, is such that the latching plate or wing 10 is retained at substantially right angles to the base plate 5 and in position to effectively prevent the 90 lower sash from being moved relatively to the upper sash except within the limits permitted for ventilation.

In order that the wing or latching plate 10 may be moved to position and retained to 95 permit normal operation of the upper and lower sashes relatively to each other, I have pivoted as at 19 adjacent the upper edge of the base plate 5, the catch 20 which is provided with an extended portion 21 and an 100 overturned part 22. This overturned part 22 is arranged to encompass the upper edge of the latching plate 10 when the same is forced closed against the action of the spring 11 for position adjacent the base plate 5.

It is quite evident that an intruder manipulating with a stick from the exterior of the window could not possibly close the latching plate 10 and then throw the catch 20 down to position to retain the same in its closed 110 position because the moment the plate 10 was released in order to operate the latch 20, it

would assume the position illustrated in Figure 1 with the result that intrusion would be prevented, due to the inability of the intruder to manipulate the sashes.

It is evident, therefore, that I have provided a window stop device which, when the catch member is not in use, will remain open at all times and cannot be closed by manipulation from the outside of the window to permit intrusion.

It is also evident that I have provided a stop which can be placed at a suitable position on the upper sash to prevent operation of the lower sash to permit an intruder to enter the room.

It is also evident that I have provided a stop member having a latching plate which is normally held in latching position and one which cannot be manipulated from a remote point without the use of two instruments, one to close the latching plate and the other to throw the latch into engaging position, thereby effectively preventing any chance of an intruder from operating the stop to permit operation of the sashes.

While I have illustrated and described my invention with some degree of particularity, I realize that in practice various alterations therein may be made. I therefore reserve the right to make any changes in the construction or in the details of construction or arrangement which may occur to me, and also to any equivalents thereof, and further I desire it to be understood that my invention is not limited to the exact construction shown and described, since it is my intention that my rights be limited only to the specific combination of parts and arrangement as shown and described, and that all changes and equivalents thereto, which do not constitute a departure from the spirit of the invention, be reserved to me.

It is my desire that the following claims be construed to cover all such changes and equivalents as fall within the true spirit and scope of my invention.

right and privilege of changing the form of 30 the details of construction or otherwise altering the arrangement of the correlated parts without departing from the spirit of the invention or the scope of the appended claim.

Having thus described my invention what I claim as new and desire to secure by United States Letters Patent is:—

The combination with the upper sash of a window, of a base plate secured thereto, a latch plate having a lower flanged extension hinged to said base plate and arranged to overlie the lower sash to limit the opening movement thereof, a spring supported on the hinge and having free ends, one of which is arranged to yieldably maintain the latch plate open, an eye punched in the base plate and in the latch plate for the reception of the free ends of the spring and a catch pivotally secured adjacent the upper edge of the base plate and having a turned over portion for engaging the upper edge of the latch plate whereby the same can be retained in closed position to permit relative movement of the sashes.

In testimony whereof I affix my signature.

CARL BURHENNE. [L. S.]
